No. 761,612.

PATENTED MAY 31, 1904.

R. G. J. SANDIFER.

CAR FENDER.

APPLICATION FILED FEB. 26, 1904.

NO MODEL.

UNITED STATES PATENT OFFICE.

ROBERT G. J. SANDIFER, OF HANNIBAL, MISSOURI, ASSIGNOR OF ONE-HALF TO ISAAC H. CHRISTOPHER, OF HANNIBAL, MISSOURI.

CAR-FENDER.

SPECIFICATION forming part of Letters Patent No. 761,612, dated May 31, 1904.

Application filed February 25, 1904. Serial No. 195,258. (No model.)

To all whom it may concern:

Be it known that I, ROBERT G. J. SANDIFER, a citizen of the United States, residing at Hannibal, in the county of Marion and State of Missouri, have invented a new and useful Car-Fender, of which the following is a specification.

This invention relates to car-fenders, and has for its objects to produce a comparatively simple inexpensive device of this character which may be readily operated and one which in practice will effectually prevent a person or other obstruction upon the track being struck by an approaching car.

To these ends the invention comprises the novel features of construction and combination of parts more fully hereinafter described.

In the accompanying drawings, Figure 1 is a perspective view of the improved device; Fig. 2 is a top plan view of the fender, showing the pivoted wings or guards open in full lines and closed in dotted lines. Fig. 3 is a detail sectional elevation on the line 3-3 of Fig. 2.

Referring to the drawings, 1 designates a car-platform of the usual construction, to the front of which there is preferably attached in some suitable manner a supporting member or timber 2 for sustaining the fender and its operating mechanism, which are attached to and carried thereby.

Secured at its rear end centrally to and projecting forwardly from the timber 2 is a horizontal guide rod or member 3, on which is slidably mounted for longitudinal reciprocation a sleeve or collar 4, there being provided upon the forward end of the guide a rubber or other suitable bucking-head 5, while the sleeve is provided with a pair of spaced ears 6, between which is pivoted or otherwise secured the forward end of an operating member, preferably in the form of a rack-bar 7, extended rearwardly through an opening or other guideway 8, formed through the timber and platform. The teeth of the operating-rack are engaged by a gear or other actuating device 9, fixed upon a vertical shaft 10, stepped at its lower end in a bearing 11 beneath the platform and provided at its upper end with

a suitable operating-crank 12. It is apparent from this arrangement that when the shaft is rotated in one direction the sleeve 4 will be moved forwardly on its guide and rearwardly on the latter when the shaft is rotated in the other direction.

Pivoted at their rear ends to the timber 2 to swing in a horizontal plane is a pair of oppositely-disposed forwardly-converging guard members or wings 13, which normally lie in closed position with their forward ends meeting in advance of the forward end of the guide 3, attention being directed to the fact that these members co-operate to produce a primary fender, which adjacent to its rear end is of a transverse width somewhat greater than the transverse width of the car for a purpose which will later appear. The guards 13, which are preferably composed each from a single length of suitable rod metal bent to the form as herein shown for producing a pair of vertically-spaced frame-bars 14, are connected, respectively, with the sleeve 4, each by means of a pair of rods or similar connecting elements 15, pivoted at their inner ends to the sleeve and at their outer ends, respectively, to the frame-bars 14 at a point adjacent to the forward end of the guard, which latter has disposed between its frame-bars a filling 16, of wire fabric or the like.

Pivoted to the timber 2 to swing in a vertical plane is a horizontally-disposed supplemental guard or fender 17, comprising a supporting-frame formed, preferably, from a single piece of metal and of a length to extend transversely across the car-track, this frame being provided with a suitable filling of wire network.

In practice the guards 13 normally occupy the dotted position, as in Fig. 2, with the sleeve 4 disposed rearwardly on the guide 3, the parts being retained in this position through the medium of the rack-bar 7 and gear 9. With the parts in this position if the fender comes in contact with a person or other obstruction upon the track the shaft is manipulated for moving the sleeve 4 forward through the medium of the gear and rack-bar, thereby opening the guards to the full-line position,

- as seen in Fig. 2, and throwing the obstruction to one side of the track. It is to be noted in this connection that the obstruction will, owing to the rear portion of the wings lying in a transverse plane beyond the sides of the car, be moved entirely out of the path of the latter. Should a person be caught between the guards of the primary fender, they will be thrown onto the secondary fender.
- 10 From the foregoing it will be seen that a simple efficient device is produced which is admirably adapted for the attainment of the ends in view; but it is to be understood that minor changes may be made in the details 15 herein set forth without departing from the spirit of the invention.

Having thus described the invention, what is claimed is—

1. In a device of the class described, the 20 combination with a car, of a pair of normally closed forwardly-converging guards pivotally connected with the car to swing in a horizontal plane and adapted when closed to project at a point between their ends beyond the trans- 25 verse plane of the car, a guide projecting forwardly from the latter, a sleeve slidably connected with the guide, operative connections between the sleeve and guide, and means for actuating the sleeve to operate the guards.
2. In a device of the class described, the 30 combination with a car, of a pair of normally closed forwardly-converging guards pivotally connected with the car to swing in a horizontal plane and adapted when closed to project at a point between their ends beyond the trans- 35 verse plane of the car, a guide projecting forwardly from the latter, a sleeve slidably connected with the guard, rods connecting the sleeve and guards, and means for operating 40 the sleeves to actuate the guards.
3. In a device of the class described, the 45 combination with a car, of a pair of normally closed forwardly-converging guards pivotally connected with the car to swing in a horizontal plane and adapted when closed to project at a point between their ends beyond the trans-

verse plane of the car, a guide projecting forwardly from the car, a sleeve slidably connected with the guide, operative connections between the guards and sleeve, an operating member connected with the latter, and means for actuating the operating member.

4. In a device of the class described, the combination with a car, of a pair of normally closed forwardly-converging guards pivotally 55 connected with the car to swing in a horizontal plane and adapted when closed to project at a point between their ends beyond the trans- 60 verse plane of the car, a guide projecting forwardly from the car, a sleeve slidably connected with the guide, operative connections between the guards and sleeve, a rack-bar connected with the latter, an operating-shaft, and a pinion carried by the shaft and engaging the rack-bar.

5. In a device of the class described, the combination with a car, of a pair of coöperating guards pivotally connected with the latter to swing in a horizontal plane, a guide projecting forwardly from the car, a sleeve 70 slidably connected with the guide, operative connections between the guards and sleeve, and means for actuating the latter to operate the guards.

6. In a device of the class described, the 75 combination with a car, of a pair of coöperating guards pivotally connected with the latter to swing in a horizontal plane, a guide projecting forwardly from the car, a sleeve 80 slidably connected with the guide, operative connections between the guards and sleeve, a rack-bar connected with the latter, an operating-shaft, and a pinion carried by the shaft and engaging the rack-bar.

In testimony that I claim the foregoing as 85 my own I have hereto affixed my signature in the presence of two witnesses.

ROBT. G. J. SANDIFER.
